(57) **CLAIM**

We claim the ornamental design for a battery pack, as shown and described.

DESCRIPTION

FIG. 1 is a perspective view of the battery pack showing our new design;

FIG. 2 is a front view of the battery pack;

FIG. 3 is a rear view of the battery pack;

FIG. 4 is a left-side view of the battery pack;

FIG. 5 is a right-side view of the battery pack;

FIG. 6 is a top plan view of the battery pack; and,

FIG. 7 is a bottom plan view of the battery pack.

The broken lines in the figures illustrating portions of the battery pack form no part of the claimed design.
